APPARATUS FOR MARKING ARTICLES

Hollis W. Norman and Richard Stech, Govans,
Md., assignors to Western Electric Company,
Incorporated, New York, N. Y., a corporation of
New York

Application September 6, 1940, Serial No. 355,622

4 Claims. (Cl. 101—38)

This invention relates to an apparatus for marking articles and more particularly to a fuse marking apparatus.

An object of the invention is to provide an effective and efficient apparatus for marking articles.

In accordance with one embodiment of the invention an apparatus is provided wherein a carrier revolvably supports an article to move it to a marking position where a marking tool revolves the article to make a circular mark thereon.

A complete understanding of the invention may be had by reference to the following description taken in conjunction with the accompanying drawing, in which

Fig. 1 is a side elevation of an apparatus embodying the invention;

Fig. 2 is a fragmentary sectional side of a portion of the apparatus shown in Fig. 1, and

Fig. 3 is a sectional view taken on line 3—3 of Fig. 1.

Referring now more in detail to the drawing a hopper 5 is shown in which a quantity of fuse shells to be marked may be placed. The fuse shells are elongated tubes of fiber or other insulating material having fuse elements therein and provided at their ends with terminals to which electrical contact may be made. The fuse shells are placed in the hopper with their axes all extending in the same direction and the lowermost fuses lie upon the periphery of a drum 6. The drum 6 may comprise a pair of end plates 7 with notches 8 at predetermined intervals along their periphery and mounted upon a shaft 9. Between plates 7 are a plurality of rolls 11 rotatably mounted in the end plates 7 and the peripheries of the rolls are provided with a layer of friction material 12 such as cork or the like. The drum 6 is intermittently rotated and upon rotation each of the notches 8 will receive a fuse from the hopper and a fuse thus removed from the hopper will lie on the peripheries of two adjacent rolls so that the fuse may be readily rotated. The means for intermittently rotating the drum may consist of a geneva movement comprising, for instance, a disk mounted on shaft 9 which has a plurality of notches 13 in its periphery corresponding to the number of notches 8 in the end plates 7. A second disk 14 is mounted on a shaft 15 and has a stud 16 mounted thereon so that upon counterclockwise rotation of the disk 14 the stud 16 will successively engage successive notches 13 and intermittently rotate the drum. The shaft 15 has a pulley 17 mounted thereon

which may be driven by a motor 18 through a belt 19.

The intermittent motion of drum 6 is such that a fuse 21 will be carried to a heated knurled marking member 22 and stopped. The knurled member 22 is supported between the arms of a bifurcated support 23 threaded into the end of an electric heater 24 of the type commonly used in soldering irons which is heated by plugging its cord into an ordinary electric outlet. This heating element together with the knurled marking device is carried upon a slide 25, the lower end of which is dove-tailed as shown at 26 in Fig. 3 and slides in a guide 27 mounted upon the frame 10 28 of the apparatus. The slide 25 also carries a roller 31 and adjacent this roller is a shaft 32 rotated by a pulley 33 through a belt 34 driven by a pulley on shaft 15. The shaft 32 carries a cam 35 and upon rotation of shaft 32 the cam 15 engages roller 31 moving the slide 25 to the right as viewed in the drawing. The slide is continuously urged to the left by a compression spring 40 which may be adjusted to regulate the pressure to any desired value. When a fuse 21 reaches the position shown in Fig. 2 the high point of cam 35 will have passed the roller 31 and spring 41 will urge the heated knurled marking member into engagement with the periphery of the fuse. The knurled marking member is 20 mounted upon a shaft 42 and this shaft also carries a pulley 43 driven by means of a belt 44 which in turn is driven by a pulley 45 mounted on shaft 32 which carries the cam 35. The knurled marking member 22 is therefore continuously driven but it comes in contact with the fuse only when permitted to do so by the action of cam 35. When the heated and knurled marking member comes in contact with the fuse which is rotatably supported on the drum 6, the fuse 25 will rotate and a circular knurled mark will be impressed upon the fuse. It is, however, usually also desirable to impart a distinctive color to the knurled mark and for this purpose a coloring tape 51 is fed between the marking device and the fuse. A supply of the marking tape is provided upon a reel 52 mounted on arms 53 secured to the hopper. The shaft carrying the supply reel 52 also preferably carries a brake drum 54 against which a spring 55 urges a brake shoe 56 so that the reel will supply tape only when tape is positively withdrawn therefrom. In order to indicate when the tape supply is exhausted an arm 57 is pivotally mounted to lightly urge a roller 58 against the tape. When the tape 30 is exhausted the arm will fall down against a 35 40 45 50 55

stop 59 and the end of the arm will actuate a microswitch 61 to stop the apparatus. The tape passes from the supply reel 52 over a roller 63 between the knurled marking member and a fuse and thence downwardly between a pair of feed rolls 65 and 66. The feed roll 65 is driven by means of a belt 67 from a pulley mounted on shaft 32 while the roll 66 is driven only by contact with roll 65. The roll 66 is carried by a pair of arms 68 pivoted at 69 and urged against the roll 65 by means of a spring 71. One of the arms 68 has a lateral projection 72 engaged by a rod 73, the opposite end of which is secured to a similar lateral projection 74 on a bracket 75 carried by the slide 25. It will be noted that the marking tape is thus advanced both by the rotation of the marking member 22 and by the rotation of the feed rolls 65 and 66. However, when the marking member is moved away from the fuse the tape will not be advanced by the marking member and at the same time rod 73 will pivot the roll 66 away from the positively driven roll 65 so that the take-up rolls also will not advance the tape during this interval. At this time the brake drum 54 and brake shoe 56 tend to prevent advancing of the marking tape and the tape at its lower end is also engaged by a pair of resilient members 81 and 82 attached respectively to the stationary arm carrying roll 65 and one of the pivoted arms 68 carrying roller 66. These resilient members are so arranged as to clamp the tape therebetween whenever the roll 66 is moved out of engagement with the roll 65.

In the operation of the apparatus the drum 6 will be intermittently rotated to advance a fuse to the marking position. The marking member 22 will then advance against the fuse to rotate the fuse and draw a length of marking tape from the supply 52. When the marking device has rotated sufficiently to apply a circular colored impression upon a fuse it will be moved away from the fuse and the advance of the marking tape will be stopped. The marked fuse will then upon further rotation of the drum drop down an inclined chute 91.

It will be understood that the nature and embodiment of the invention herein disclosed is merely illustrative and that many changes and modifications may be made therein without departing from the spirit and scope of the invention.

What is claimed is:

1. An apparatus for marking articles comprising a drum for rotatably supporting articles to

be marked, means for intermittently rotating said drum to carry an article to a marking position, a continuously rotating marking roller, means for feeding a marking tape between said marking roller and an article to be marked, means for retracting said marking roller from the marking position while an article is being advanced to the marking position and returning said roller to the marking position when an article has reached the marking position, and means for operating said tape feeding means only while said roller is in the marking position.

2. An apparatus for marking articles comprising a support for rotatably supporting an article in a marking position, a continuously rotating marking roller, a heat conducting support for said roller, electric heating means associated with said support, a cam for intermittently moving said roller from the marking position and returning it to the marking position, and means cooperating with said cam for feeding a marking tape between said roller and an article to be marked only while the roller is in marking position.

3. An apparatus for marking articles comprising a support for rotatably supporting an article in a marking position, said support including a pair of rolls having resilient surfaces to yieldably support an article, a continuously rotating marking roller, means for retracting said marking roller from the marking position while an article is being advanced to the marking position and for returning the roller to the marking position when the article has reached the marking position, means for feeding a marking tape between the article to be marked and the marking roller, and means for rendering said last-mentioned means effective only while the marker is in the marking position.

4. An apparatus for marking articles comprising means for rotatably supporting an article in a marking position, a marking roller, means for rotatably supporting the marking roller, means for heating the supporting means to supply heat to the marking roller, means for intermittently moving said marking roller from the marking position and returning it to the marking position, and means cooperating with said last mentioned means for feeding a marking tape between said rollers and an article to be marked only while the marking roller is in marking position.
